UNITED STATES PATENT OFFICE

FRIEDRICH BARTLING, OF MUNICH, GERMANY

ROTARY HEARTH OVEN

Application filed June 27, 1927, Serial No. 201,953, and in Germany January 15, 1927.

This invention relates to ovens of the rotary annular hearth type. For the purpose of the present invention this type of oven may be more particularly defined as an oven adapted for continuous operation and wherein the chamber for the material to be heat treated has the form of an annular channel closed at the top and open at the bottom. The opening at the bottom of this 10 annular channel is closed by a continuously rotating annular hearth, the so-called rotary plate. The material for treatment is distributed in a uniform layer on this hearth plate and carried thereby from the charging 15 locality, through the oven chamber, to the place where discharge of the material is effected. In this manner heat treatment of the material is carried out in the oven chamber. The oven is generally heated indirectly 20 by separate external heating means, the oven gases (for instance, vapors, or gases resulting from distillation of the material or otherwise arising) being carried off through special separate ducts provided for this purpose. Between the stationary oven walls 25 and the rotating hearth plate it is necessary to provide special gastight sealing means. The hearth plate is usually rotated through the agency of suitable supporting and driv- 30 ing devices arranged beneath it.

A particularly effective method of heating in ovens of this kind is obviously the direct heating of the working hearth from below but this method is fraught with difficulties 35 owing to the fact that the hearth is maintained in continuous rotation. In the first place this method of heating requires that the space under the rotating hearth plate be kept as free as possible from supporting 40 and driving means. Yet even if this be done, heating by means of currents of hot gases (as has been almost universal hitherto) is unsatisfactory, since the heat imparted 45 to the travelling hearth plate varies irregularly as between different parts of said plate and fluctuates in intensity. In particular when the material to be treated is spread out on the working hearth in an extremely 50 thin layer, as is always the practice of the

present inventors, such irregular heating is accompanied by disastrous results.

Having regard to these difficulties, the fundamental idea of the present invention consists in using, for the underneath heating 55 of the revolving hearth in rotary annular hearth plate ovens, the so-called "flameless combustion," also known by the names of "surface" or "contact" combustion. It is known that this type of combustion is based 60 on the provision of a porous fireproof contact mass, or radiant body, which is fed through burners with combustible gases, which raise the mass to incandescence, whereby the combustible gas is burned with- 65 out the formation of any flame but with the evolution of a great amount of heat.

In the practical application of this idea, according to the present invention, the space beneath the annular rotating hearth is filled 70 up with a radiant body which can be heated by the method of flameless combustion.

In conjunction with various arrangements of ovens proposed by the present inventors, the new heating means can be applied in sev- 75 eral different ways.

In a preferred arrangement the radiant body is placed in a stationary annular channel under the rotating hearth plate. This may be accomplished by filling the walled 80 annular channel, into which the burner noz- zles open at intervals, with a loose mass, such as pieces of fire clay, for example, which is suitable for flameless combustion.

When this arrangement is adopted the 85 supporting and driving means cannot of course be accommodated in the space underneath the rotating hearth, as they normally are.

A further feature of the invention con- 90 sists, therefore, in a novel arrangement of the supporting and driving means for such rotating hearths in ovens of the type de- scribed, when such hearths are heated from underneath.

According to this feature, the hearth plate 95 is provided at each side with lateral exten- sions or outriggers projecting radially from it and serving to space it suitably from the supporting and driving means proper, which 100

is arranged outside the area covered by said hearth. By disposing the parts of the mechanism in this manner the sensitive supporting and driving means are withdrawn 5 from the direct influence of the furnace, while the whole undersurface of the rotating hearth is left exposed to the action of the heating agent. Moreover, distortion and warping of the hearth plate, under the action of the heat, are, to a great extent, prevented by the more stable support which is secured by the new arrangement.

In this improved oven the hearth plate itself may be made flat, in the usual way, 15 but in ovens of this kind, in which the heat proceeds exclusively from below, through the hearth plate, it is found that the latter, being subject to irregular and fluctuating heat intensities, has a tendency to become distorted or warped. Such changes in the original shape of this annular plate have very inconvenient results, both as regards the keeping of the joints between the interior of the oven and the rotating plate gastight and also 20 in respect of maintaining regular working of the said plate. An annular hearth plate, when warped in this manner, sets up knocking in the course of its rotary movement, so that, when an attempt is made to distribute 25 the material to be treated on to the working surface of the hearth in a very thin layer, irregularities occur in the thickness of the said layer which greatly impede the working of the oven and prevent uniform 30 treatment of the material.

In one preferred constructional form of oven according to this invention the above named defect is overcome by giving to the annular hearth plate an upwardly arched 40 or vaulted cross section, conforming, if desired, to the arc of a circle or to any similar symmetrical curve.

At the same time the underside of the hearth plate is preferably provided with a 45 network of stiffening ribs.

When pulverulent material is to be distributed in a very thin layer on this hearth plate, it is advantageous to break up or roughen its working surface, as by means 50 of grooves, furrows, ribs, humps or the like, adapted to entrain the material under treatment, for the better transport of the same through the oven.

The advantages of using arched hearth 55 plates in rotary annular hearth plate ovens reside firstly, in the great stability of such plates, secondly in the more efficient transference of heat achieved by their use and, thirdly, in a better compensation of the ex- 60 pansion and distortion arising through fluctuations of temperature. The system of ribs provided on the underside of the hearth plate, besides serving to strengthen the same but also ensures more efficient transference 65 of heat to the upper surface thereof and

compensates temperature fluctuations by reason of the storing up of radiant heat in the said system of ribs. Thus a uniform temperature is ensured over the whole of the upper surface of the hearth plate and the material to be heated is everywhere penetrated uniformly by the heat.

According to the present invention the hearth is supported by annular box girders which are arranged on each side thereof and supported on separate roller blocks running on an endless line of rails. In these girders may be incorporated devices such as sand gutters, which provide a gastight seal between the oven and the heating chamber 80 and also between the oven and the outer atmosphere.

As it is of paramount importance that the hearth plate proper, which is subjected to fairly strong and fluctuating heating action, be able to expand and contract freely, without being prevented from so doing by the supporting structure, the invention provides for the insertion of link members between the annular carriers and the roller blocks, on the one hand and between the annular carriers and the supporting arms of the hearth, on the other. This yielding arrangement may conveniently be completed by providing for mutual radial movability 95 as between the supporting arms and the annular carriers.

In another arrangement of rotating hearth designed by the inventors, the rotary plate is divided into two superimposed annular members connected by supporting means, the lower member, which closes in the oven chamber, carrying sealing, supporting and driving means, while the upper one, which carries the spread out layer of material to be treated, is spaced at such a distance above the lower plate within the oven chamber that it can be heated from below. In this kind of hearth the space between the working plate and the supporting plate may, according to the invention, be used for the accommodation of a radiant body which then partakes of the rotary movement of the hearth itself. This radiant body cannot, of course, consist of loose material but may, in accordance with this invention, consist of a grid structure of fire clay or equivalent material, the spaces in which can be filled up by a suitable loose mass. The supply of the combustible gas may then conveniently be effected by means of burner nozzles penetrating the side walls of the furnace.

Various constructional forms of apparatus according to the present invention are shown in the accompanying drawings, in which:

Figures 1 and 2 show the general arrangement of the new oven in vertical axial section and in plan view, respectively.

Figure 1^a shows a somewhat modified constructional form of the hearth plate.

Figure 3 illustrates another constructional form of the radiant body and hearth substantially in vertical section on line 3—3 of Fig. 4.

Figure 4 is a section on the line 4—4 of Fig. 3.

In the constructions illustrated, the working hearth proper, designated by the numeral 1, separates the annular oven chamber 2 from the heating channel 3 which is likewise annular.

In the example of construction shown in Figures 1 and 2 the supporting and driving means are arranged on both sides of the hearth plate and jut out sideways therefrom. The space underneath the working hearth is therefore perfectly free and it is used to form a spacious heating channel 3, which, according to the present invention, is filled with a loose mass. This loose mass consists of the materials usually employed for flameless combustion, which materials must be fireproof and porous and must present a rough external surface.

Heating is effected by burner nozzles 25 distributed at intervals around the circumference of the oven and supplying the combustible gas to the heating channel from below.

The annular hearth plate 1 is arched in the construction shown in Figure 1 so that the inner and outer edges of the annular hearth are lower than its crown line and flat in the construction shown in Figure 1^a, and in both cases has its walls as thin as possible. On its underside it is provided with a network of stiffening ribs 4, while its upper surface, if pulverized or dusty material is to be treated, may be roughened, as by furnishing it with ribs, grooves, furrows, humps or the like, which entrain the material and act as carriers therefor. The heated material gives off gaseous products, which can escape through branches in the top of the oven or be drawn off. The material flows on to the annular hearth through a delivery apparatus 6, which, however, forms no part of the present invention, while the completely treated material is generally drawn off from the hearth plate by suction means.

According to the present invention radially projecting extensions or outriggers 7 are affixed to the working hearth and these protrude into an annular space arched over by the top of the oven 21 and lying outside the range of influence of the heating channel 3. Each of the outriggers terminates in a ball pan 8 which is supported on a large steel ball or a hemispherical bearing 9. The steel ball itself rests on or in a hemispherical bearing surface or socket 10, formed in a sliding shoe 11. If the bearings 9 are

constructed as hemispherical bearings, the half balls which act as substitutes for the complete steel balls aforesaid are made integral with the sliding shoes themselves, that is to say, the sliding shoes are constructed with a hemispherical top and a flat sliding bottom. In order that the sliding shoes of the bearing surfaces 10 may be able to move radially there are fixed to the box girders 13 or, more particularly, to the annular superstructures 14, which rise centrally of each box girder, sliding plates 12 furnished on both sides with lugs or flanges between which the sliding shoes 11 can move radially. The side walls of the box girders 13 form, together with outer and inner walls 15 and 16, sand gutters which act as seals between the oven chamber 2, the outer air on the one hand and the heating channel on the other. Another sand gutter 16¹ may be provided to act as a seal between the heating chamber and the outer air. Each annular box girder 13 is carried by a number of roller blocks 17 which run on endless lines of rails 18. The roller blocks carry for driving purposes a circular rack 19 which is kept in rotation by a driving pinion 20. Between each roller block 17 and the box girder 13 is interposed a pivot member 22, which permits of mutual oscillatory adjustment as between the box girders and the rollers.

In the constructional form shown in Figures 3 and 4 the rotary hearth structure rotates in the annular oven chamber 51. This rotary hearth structure comprises two superposed plates, namely, the working or hearth plate 53 and the supporting plate 54. The supporting plate is mounted on the bearer 55 with the travelling frame 56 and also the sealing members 57. By means of suitable supports 58 the working plate 53, on which the material to be treated is spread out, is held above the supporting plate 54. Around the oven chamber 51, between the treatment chamber proper and the space between the plates 53 and 54, additional seals 59 may be inserted, particularly when the material under treatment has to be distilled, in which case it is desirable to obtain the gases resulting from distillation in as pure a state as possible.

The passage-like chamber between the plates 53 and 54 is filled, according to this invention, by a light grid structure 60, of fire clay or other fireproof and porous material. The radiant bodies so formed partake of the rotary movement of the hearth and must therefore be made as light as possible. The combustible gas is supplied by one or more burner jets 61, and the products of combustion may be carried away through a pipe 62.

Claims:

1. A rotary annular hearth oven com-

prising an annular oven chamber, an annular working hearth plate rotatable in said chamber, said annular hearth plate being upwardly arched in cross section, said chamber having a furnace space beneath the annular working hearth, a radiant body in said furnace space, and means fixed to the chamber walls to supply combustible gas to said body for flameless combustion therein whereby the parts of the roasting hearth are heated uniformly by successively passing said means.

2. A rotary annular hearth oven comprising an annular oven chamber, an annular working hearth plate rotatable in said chamber, said annular hearth plate being upwardly arched in cross section, said chamber having an annular furnace space beneath and concentric with the annular working hearth, a radiant body in said furnace space comprising a loose mass of refractory material suitable for flameless combustion, said mass extending upward into the arch of the hearth plate, and a plurality of burner nozzles fixed in position with respect to said chamber and opening at spaced intervals into said furnace space to deliver combustible gas into said loose mass for flameless combustion therein whereby the parts of the rotating hearth are heated uniformly by successively passing the locations of the nozzles.

3. A rotary annular hearth oven comprising an annular oven chamber, an annular working hearth rotatable in said chamber, lateral extensions mounted on and projecting from said hearth at each side thereof, an annular supporting surface concentric with and mounted at each side of said annular hearth, bearing members movable radially on said supporting surfaces and having hemispherical tops, bearing pans on said extensions to rest on said hemispherical bearing members and thereby support said hearth, means to cause said surfaces to move concentrically with the hearth, and a furnace beneath said working hearth.

4. A rotary annular hearth according to claim 7, in which a plurality of bearing members are provided having flat bottoms slideable along said surfaces, and bearing pans on said extensions to rest on said hemispherical bearings and thereby support said hearth, annular tracks disposed concentric with said annular hearth at each side thereof, means traveling on said tracks and supporting said extensions and including pivotal connections having axes at a right angle to the respective radii of the annular hearth, and a furnace beneath said working hearth.

5. A rotary annular hearth oven comprising an annular oven chamber, an annular working hearth rotatable in said chamber, annular tracks concentric with and on each side of said annular hearth, an annular

girder arranged above each of said tracks, roller blocks traveling on the tracks and supporting the respective girders, individual pivots between the respective roller blocks and the said girder, and means projecting from said hearth and carried by said girders to support said hearth without interference with the furnace beneath the same, and a furnace beneath said hearth.

6. A rotary annular hearth oven comprising an annular oven chamber, an annular working hearth plate rotatable in said chamber, said chamber having a furnace space beneath the annular working hearth plate, a radiant body in said furnace space, means fixed to the chamber walls to supply combustible gas to said body for flameless combustion therein whereby the parts of the rotating hearth plate are heated uniformly by successively passing said means, annular supports for the annular hearth plate at each side thereof, and seals comprising cooperating members mounted on said hearth, said furnace chamber and said supports whereby to prevent the passage of gas from the furnace space to the atmosphere or to the upper surface of said hearth plate, and the passage of gas from the upper surface of said hearth plate to the atmosphere.

In testimony whereof I have signed my name to this specification.

FRIEDRICH BARTLING.
